UNITED STATES PATENT OFFICE.

HERBERT L. SARGENT, OF SALEM, MASSACHUSETTS, ASSIGNOR OF ONE-HALF TO LEONARD B. PICKERING, OF SALEM, MASSACHUSETTS, AND ONE-HALF TO MARY E. SARGENT, OF DANVERS, MASSACHUSETTS.

INKING DEVICE FOR PRINTING-PRESSES.

1,358,021.

Specification of Letters Patent.

Patented Nov. 9, 1920.

Application filed April 29, 1918. Serial No. 231,334.

To all whom it may concern:

Be it known that I, HERBERT L. SARGENT, a citizen of the United States, residing at Salem, county of Essex, and State of Massachusetts, have invented an Improvement in Inking Devices for Printing-Presses, of which the following description, in connection with the accompanying drawings, is a specification, like characters on the drawings representing like parts.

The invention to be hereinafter described relates to inking devices for printing presses.

These presses are usually provided with an ink receptacle, adjacent the rotary ink distributing disk, to supply ink to rollers which pass over the disk and across the face of the form to ink the same. Different classes of work require the ink to be fed from the ink receptacle at widely varying speeds and with a nicety of gradation. For example, a hard, highly glazed paper requires less ink than a soft, rough paper. Also, for any one class of work the same amount of ink should be fed to the rollers and applied to the form for each impress, in order that successive impresses may be of uniform character.

One of the objects of the present invention is to provide simple and effective means whereby the ink may be fed from the ink receptacle with a desirable nicety of adjustment in conformity with the requirements of the character of work to be produced, and whereby the ink may be fed at a uniform rate for production of successive impresses of the same quality for any selected class of work.

Another object of the invention is to provide an inking device having a receptacle which may be easily applied to and removed from the press to facilitate replenishing the supply of ink and substitution of inks of different color or character.

And still another object is to provide simple and effective means for transmitting movement from a rotating member of the press to means for feeding the ink from the ink receptacle.

With the aforesaid and other objects in view, the character of the invention will be best understood by reference to the follow-

ing description of one good form thereof shown in the accompanying drawings, wherein:

Figure 1 is a side elevation of a portion of a printing press equipped with an inking device embodying the invention;

Fig. 2 on an enlarged scale is a side elevation of the inking device;

Fig. 3 is a transverse section taken on line 3—3 of Fig. 2;

Fig. 4 is a side elevation of the lower end of the ink cylinder;

Fig. 5 is a plan of the inking device;

Figs. 5^a and 5^b show portions of the arm and plate containing openings through which the reciprocating cone head extends;

Fig. 6 is a vertical section taken on line 6—6 of Fig. 5;

Fig. 7 is a plan of the controller ratchet;

Figs. 7^a, 7^b and 7^c show details to be referred to;

Fig. 8 is a plan of the notched disk driven by the controller ratchet;

Fig. 9 is a plan of the ratchet connected to the piston feed nut;

Fig. 10 is a plan of the pawl for engagement with the notched disk; and

Fig. 11 is a vertical section taken on line 11—11 of Fig. 10.

Referring to the drawings, and more particularly to Fig. 1, wherein is shown a portion of a printing press including a platen 1 opposed to a form 3 carried by a stationary head 5 which also supports the rotary ink distributing disk 7. Ink rollers 9 are adapted to move over said disk under the control of rods 11 adapted to slide in an oscillatory frame 13, said rods being urged in a direction to press the rolls against said disk by coil springs 15 encircling said rods, and confined between one end of said frame and pins 17 extending through said rods. The oscillatory frame 13 may be rocked to cause the rollers to reciprocate over the ink distributing disk and form to ink the latter, and the oscillatory platen may be rocked toward the head to produce the impress by mechanism well known in the art, and therefore, unnecessary to show and describe herein.

The inking device shown herein as one good form of the invention comprises an ink

receptacle conveniently in the form of a cylinder 19 (Figs. 2 and 6) having a head 21 at its lower end provided with a discharge slit 23 (Fig. 3) and having an outwardly projecting flange 25 conveniently rectangular in outline, formed to present an upturned lip 27 to facilitate passage of the ink rollers between the cylinder head and the ink distributing disk, as more fully 10 hereinafter described.

Suitable means may be provided to position the ink cylinder adjacent the ink distributing disk. To accomplish this, in the present instance of the invention, a ring 29 (Figs. 2 and 6) is provided formed to fit the cylinder and projecting laterally from the lower end of an arm 31 depending from a plate 33. The upper end of the cylinder is open and adapted to fit in a shallow 20 socket 35 on the under side of the plate 33. To detachably secure the cylinder in working position in the ring and socket, the cylinder may have a lug 37 thereon adapted to pass through a slot 39 in the ring, the construction being such that the cylinder may be slid up through the ring and may be given a rotative adjustment to cause the lug to register with the slot. Then further upward movement of the cylinder will cause 25 the upper end thereof to be seated in the socket 35 and will bring the lug 37 above the upper edge of the ring 29. Slight rotation of the cylinder will move the lug 37 out of registration with the slot and lock the cylinder in position. The arm 31 may be secured by screws 41 to a curved bracket 43 (Figs. 1 and 6) having its lower end connected to the upper end of the oscillatory head by a bolt 45 having a wing nut 47. A 30 flange or shoulder 49 formed on said bracket may engage a part of the head to limit rocking of the bracket in a contra-clockwise direction (Fig. 1). The construction is such that on release of the wing nut 47, the bracket may be rocked in a clockwise direction to allow ready insertion of the ink cylinder into its ring and socket and removal 35 therefrom. A plurality of cylinders such as described may be provided to contain inks of different color or character as required. The construction is such that one cylinder may be quickly and easily substituted for another.

Next will be described means for feeding 55 the ink from the cylinder. To accomplish this, in the present instance, a piston 51 (Fig. 6) may be fitted in said cylinder and provided with a disk pad 53 beneath the same to prevent leakage of ink up past the piston. A stem 55 projects upwardly from the piston through the open end of the cylinder and through an opening in the plate 33, said stem being threaded to a sleeve nut 57 having a flange 59 for engagement with 60 the under face of the plate 33 to confine said

nut against upward movement. Rotation of the nut will cause the stem and piston to move downward and force the ink from the cylinder through the slit 23.

An important feature of the invention relates to means for rotating the nut to feed the piston. This means, in the present instance, comprises a ratchet 61 (Figs. 6 and 9) fast on the sleeve of said nut and adapted to be advanced step by step by a pawl 63 secured by a screw 65 (Fig. 11) on the lower squared end of a pin 67 pivotally mounted in an arm 69 fulcrumed on the sleeve of the nut and projecting laterally therefrom, as will be noted in Figs. 5 and 6. The pawl 70 may be urged toward the ratchet by a coil spring 71 having one end connected to the heel of said pawl and its opposite end connected to a pin 73 on the arm 69. Suitable means may be provided to oscillate said arm 75 and cause the pawl to advance the ratchet step by step. To accomplish this, the arm 69 may be urged in one direction by a coil spring 75 having one end connected to the pin 73 and its opposite end connected to a pin 77 on an arm 79 projecting laterally from the plate 33. The arm may be moved in the opposite direction by a conical head 81 tapering downward and projecting through openings 83 and 85 in the arm 69 80 and plate 33 respectively. A rod 86 projects downward from the conical head to a crank 86^a (Fig. 1) fast on a shaft 86^b which may be given one complete rotation by any suitable means each time the oscillatory platen 85 rocks toward and from the form. The construction is such that rotation of the crank 86^a will reciprocate the rod 86 and the conical head 81 in the openings 83 and 85. When the conical head is in its upward 90 position, a narrow portion of said head will occupy said openings and allow the spring 75 to rock the arm 69 and cause the pawl 63 to wipe over a tooth or teeth of the ratchet, and when the conical head moves downward, a wider portion thereof will occupy 95 said openings, cause the same to more nearly register and rock the arm 69 against the resistance of the spring 75, to cause the pawl to advance the ratchet a step equal to one 100 or more teeth depending upon the extent the pawl is retracted.

In the present instance, the ratchet 61 is provided with ninety-six teeth, so that if the pawl advances the ratchet one tooth on each reciprocation thereof, the ratchet will move one complete rotation on ninety-six reciprocations of the ratchet. This will rotate the sleeve nut and gradually move the piston downward in the cylinder and force 105 the ink through the slit in the head thereof.

As stated, it is desirable to vary the amount of ink fed according to the character of the work. To this end suitable means may be provided for preventing the pawl 63 110

from being effective to advance the ratchet on certain reciprocations thereof. For this purpose, a controlling disk 87 (Fig. 8) may be provided having notches 89 in the periphery thereof with blank portions 91 between them. This disk may be loosely mounted on the sleeve of the nut, and may be provided with suitable means for advancing the same, a step corresponding to a tooth of the ratchet 61 on each reciprocation of the pawl 63. In the present instance, this advancing means comprises a ratchet 93 mounted loosely on the sleeve of the nut and connected to the controlling disk 87 by a pin 95 (Fig. 6) projecting upward through a hole 97 in said controlling disk. To advance the ratchet 93 step by step, a pawl 99 (Figs. 6 and 11) may be loosely mounted on the pawl pin 67, referred to, and may be urged toward its ratchet by a coil spring 101 having one end connected to the heel of the pawl 99, and its other end connected to a pin 103 on the arm 69. The construction is such that each reciprocation of the arm 69 will reciprocate the pawl 99 and cause the same to advance the ratchet 93 and controlling disk 87 a step.

Coöperating with the controlling disk is a pawl 105 (Figs. 6 and 11) secured by a screw 107 to the upper squared end of the pawl pin 67, referred to. Since the pawl 63 and pawl 105 are fast on the same pin, they will rock together, and the pawl 63 will be permitted to engage the ratchet 61 each time the pawl 105 drops into a notch in the controlling disk. In the present instance, said disk contains sixteen notches, and therefore, in ninety-six reciprocations of the arm 69 the pawl 63 will be effective to advance the ratchet 61 sixteen steps, thereby reducing the speed of feed of the plunger.

It may be desirable to still further reduce the speed of feed of the plunger. To accomplish this, an auxiliary notched controlling disk 109 (Fig. 5) may be provided loosely mounted on the sleeve of the nut and relatively adjustable with respect to the controlling disk 87 to vary the effective length of the blank portions 91 thereof. In the present instance, the auxiliary controlling disk is susceptible of six positions of relative adjustment with respect to the controlling disk 87 determined by the registry of holes 111, 112, 113, 114, 115 and 116 with the pin 95, referred to, projecting upwardly from the ratchet 93.

When the hole 111 registers with the pin 95, three notches in the controlling disk 87 will be exposed and the pawl 63 will be permitted to advance the ratchet 61 three steps in ninety-six reciprocations of the arm 69 or in one complete rotation of the controlling disk. When the hole 112 registers with the pin 95, five notches of the controlling disk 87 will be exposed; when the hole 113

registers with the pin 95, eight notches of the controlling disk will be exposed; when the hole 114 registers with the pin 95, eleven notches of the controlling disk will be exposed; when the hole 115 registers with the pin 95, thirteen notches of the controlling disk will be exposed; and when the hole 116 registers with the pin 95, sixteen notches of the controlling disk will be exposed.

It may be desirable to provide further gradations of feed of the piston. To accomplish this, the extent of reciprocation of the arm 69 may be varied, so that the pawls 63 and 99 instead of advancing their ratchets a step equal to one tooth, may advance their ratchet steps equal to two or three teeth. To accomplish this, a pin 117 (Fig. 5) may be mounted on the plate 33 in the path of movement of the arm 69. When the pin 117 is in the hole 119, the arm 69 may reciprocate to cause the pawls to advance their ratchets an extent equal to one tooth; when the pin is in the hole 121, the pawls may advance their ratchets an extent equal to two teeth; and when the pin is in the hole 123, the pawls may advance their ratchets an extent equal to three teeth.

The use of the three extents of reciprocation of the arm 69 in combinations with adjustment of the auxiliary controlling disk 95 to cause its holes 111 to 116 to register with the pin 95, and the removal of the controlling and auxiliary controlling disks, enables variations of speed of feed as specified in the following table:

Number of holes in auxiliary disk registering with pin 95.	Number of teeth in extent of reciprocation of arm 69.	Number of teeth of ratchet 61 equaling the extent of advance in 96 reciprocations of arm 69.	
111	1	3	
112	1	5	
113	1	8	
114	1	11	
111	2	12	
115	1	13	
116	1	16	
112	2	20	
111	3	27	
113	2	32	
114	2	44	
112	3	45	
115	2	52	
116	2	64	
113	3	72	
Disks 87 and 109 removed	1	96	100
114	3	99	
115	3	117	
116	3	144	110
Disks 87 and 109 removed	2	192	115
Disks 87 and 109 removed	3	288	120

Thus, by the mechanism described, a very wide range of feed of the piston may be obtained with a desirable nicety of gradation of feed.

While the ratchet and controlling disks shown herein will produce feeds according to the aforesaid table, it will be understood that the invention is not limited thereto, but

that the number of teeth of the ratchets and notches in the disks may be varied as desired.

The ratchets and controlling disks may be inclosed by a protecting cover 125 which may be fitted on a cup 127 formed in the plate 33, the proper relation of said cover with said cup being determined by a projection 129 on the cup fitting a notch in said 10 cover.

When the pin 117 is shifted to the hole 121 or 123 to allow the arm 69 to advance the ratchet 93 steps equal to two and three teeth of the ratchet, respectively, it is important 15 that the position of said ratchet relatively to its actuating pawl should be such that the pawl will drop back of the second and third tooth respectively, and engage the series of teeth of said ratchet which will allow the 20 control pawl to drop into the notches of the controlling disks. To insure this operation, a tooth blanking member 131 (Fig. 7) may be pivotally mounted on a rivet 133 secured to the upper face of the ratchet 93 adjacent 25 the periphery thereof. This member has a projection 135 of an extent sufficient to cover one tooth space of the ratchet, and a projection 137 of an extent sufficient to cover two teeth spaces of said ratchet.

When it is desired to change from a one-tooth-step feed to a two-tooth-step feed the pin 117 is shifted to the hole 121. Then the actuating pawl, instead of advancing each tooth of the ratchet, will advance 30 a series of alternate teeth of said ratchet. This series should be such that it will allow the control pawl to drop into the notches of the control disks. Therefore, the blanking member is adjusted to its position 35 shown in Fig. 7^b to blank one tooth space, so that if the actuating pawl is not advancing the correct series of alternate teeth to allow the control pawl to drop into the notches of the control disks, the blanking member, in the course of a rotation of the 40 ratchet, will shift the pawl to the other series of alternate teeth and thus insure the feed of the feed ratchet.

Similarly, then it is desired to produce a three-tooth-step feed, the pin 117 is shifted to the hole 123, and the blanking member is adjusted to its position shown in Fig. 7^a to blank two teeth spaces, thereby insuring that the actuating pawl shall advance a series of 50 teeth of the ratchet which will allow the control pawl to drop into the notches of the control disks, and insure the feed of the feed ratchet. The blanking member may be adjusted to its inactive position shown in Fig. 55 7 when the ratchet is advanced single tooth steps. To hold the blanking member in its three positions of adjustment, it may have a nub 141 (Fig. 7^c) presed therefrom adapted to enter any of three holes 143 in said

ratchet. The blanking member may be of 65 a resilience such that the nub may readily slip from one hole to another.

In operation, the ink rollers will reciprocate over the ink distributing disk and the form, and each time they move over the disk 70 they will pass beneath the cylinder head 21 and receive ink delivered through the slit 23, the upturned lip 27 facilitating passage of the rollers between the head and the disk. More or less ink will be fed through the slit 75 according to the adjustments of the inking device described. The construction is such that the pawl carrying arm 69 is reciprocated once in each reciprocation of the ink rollers, and the piston may be advanced a 80 step for each reciprocation of the rollers, or it may be advanced a step in more than one reciprocation of said rollers. Thus, the feed of the ink on the rollers may be desirably proportioned to the reciprocations 85 thereof. However, the ink will always be positively fed and a selected proportionate feed maintained. As a consequence, the ink will be uniformly fed so long as each adjustment of the feed device is in effect and successive 90 impresses of uniform quality will be obtained.

It will be understood that the invention is not limited to the specific embodiment shown, but that various deviations may be 95 made therefrom without departing from the spirit and scope of the appended claims.

What is claimed is:—

1. An inking device for a printing press comprising an ink receiver, a piston therein, and means for feeding said piston to force the ink from said receiver including a feed ratchet, a pawl for engagement with teeth of said ratchet to advance the same step-by-step, a notched disk, an idler ratchet connected to said notched disk, a pawl to advance said idler ratchet step-by-step, and a pawl co-operating with said notched disk connected to said feed ratchet pawl to prevent the latter from advancing said feed ratchet. 110

2. An inking device for a printing press comprising an ink receiver, a piston therein, and means for feeding said piston to force the ink from said receiver including a feed ratchet, a pawl for engagement with teeth of said ratchet to advance the same step-by-step, and means including a pawl and notched disk for controlling the active engagement of said feed pawl with said feed ratchet. 115

3. An inking device for a printing press comprising an ink receiver, a piston therein, and means for feeding said piston to force the ink from said receiver including a feed ratchet, a pawl for engagement with said ratchet to advance the same step-by-step, and means including a pawl and notched disk for controlling the active engagement of said 125

feed pawl with said feed ratchet, and means for varying the number of effective notches of said disk.

4. An inking device for a printing press comprising an ink receiver, and means to force ink therefrom including a feed pawl and ratchet, an actuating ratchet, a pawl for advancing said actuating ratchet, and means actuated by said actuating ratchet for permitting said feed pawl to actively engage predetermined teeth of its ratchet.

5. An inking device for a printing press comprising an ink receiver, and means to force ink therefrom including a feed pawl and ratchet, an actuating pawl and ratchet, a notched controlling disk advanced by the latter, a pawl co-operating with said controlling disk for controlling said feed pawl, and a supplemental notched controlling disk for varying the effective notches of said controlling disk.

6. An inking device for a printing press comprising an ink receiver, and means to force ink therefrom including a feed pawl and ratchet, an actuating pawl and ratchet, a notched disk and pawl for controlling said feed pawl, said disk being advanced by said actuating pawl and ratchet, means to reciprocate said actuating pawl to advance its ratchet steps, each equal to one or more teeth of said ratchet, alternatively, and a tooth blanking device on said actuating ratchet to insure advance of a series of teeth of the latter which will allow said controlling pawl to drop into the notches of said controlling disk.

7. An inking device for a printing press comprising an ink receiver, and means to force ink therefrom including a feed pawl and ratchet, an actuating pawl and ratchet, a notched disk and pawl for controlling said feed pawl, said disk being advanced by said actuating pawl and ratchet, means to reciprocate said actuating pawl to advance its ratchet steps, each equal to one or more

teeth of said ratchet, alternatively, and means to insure that the actuating pawl shall advance a series of teeth of said actuating ratchet to allow the controlling pawl to enter notches of said disk.

8. The combination with a support, of an ink distributing plate thereon, inking rollers movable over said plate, an ink receiver, and means to force ink from said receiver to said rollers including a ratchet, a pawl, superposed members, one carrying said pawl and reciprocable relatively to the other, said members having apertures therein, spring means tending to move said pawl carrying member in one direction, and a reciprocable tapered element projecting through said apertures for moving said pawl carrying member in the opposite direction.

9. The combination with a support, of an ink distributing plate thereon, inking rollers movable over said plate, an ink receiver, and means to force ink from said receiver including a pawl and ratchet, a pair of relatively movable members having apertures therein, one of said members being operatively connected with said pawl, and an element of varying cross-section, projecting through said apertures and reciprocable to cause the relative movement of said members for actuating said pawl.

10. An inking device for a printing press comprising an ink receiver, a piston therein, and means for feeding said piston to force the ink from said receiver including a feed ratchet, a pawl therefor, means to reciprocate said pawl, and automatically rotated controlling means for regulating the extent of the increment advance of the ratchet by said pawl with provision for allowing said pawl to engage every tooth of said ratchet or selected teeth of said ratchet.

In testimony whereof, I have signed my name to this specification.

HERBERT L. SARGENT.
